BUFFING ATTACHMENT FOR DRAWING ROLLS

Kenneth P. Swanson, Abington, Mass., assignor to Progressive Engineering, Inc., Rockland, Mass., a corporation of Massachusetts

Application December 15, 1954, Serial No. 475,489

10 Claims. (Cl. 51—95)

This invention relates to machines for buffing the cots of the drawing rolls of spinning frames to provide them with true cylindrical surfaces, and comprises a novel and improved attachment adapted to be mounted on and employed with buffing machines now in use for this purpose.

My invention contemplates the employment of a cylindrical driving roll supported in axially fixed and true running axial alignment by and between the headstock and tailstock centers of a buffing machine, and work supporting means mounted on the machine and including two spaced members for rotatably supporting at its ends and parallel with the driving roll a drawing roll to be buffed. The attachment furthermore includes means for moving the work supporting means forwardly and rearwardly to bring the drawing roll into and out of peripheral driving engagement with the driving roll and into and out of position to be engaged by the grinding wheel. The fixed and true running driving roll is adapted to maintain and drive the drawing roll in true alignment while its cylindrical surface is being ground to close tolerances on the grinding wheel of the buffing machine. The production of a novel and improved attachment of this nature, together with means for quickly mounting it on a buffing machine, comprises the primary object of the invention.

These and other features of my invention will be more readily understood and appreciated from the following detailed description of preferred embodiments thereof, selected for purposes of illustration and shown in the accompanying drawings in which:

Fig. 1 is a front elevation of a buffing attachment embodying my invention mounted on a buffing machine of known construction,

Fig. 2 is an enlarged fragmentary plan view,

Fig. 3 is a like fragmentary plan view illustrating the parts in another position, and

Fig. 4 is an enlarged sectional view taken on line 4—4 of Fig. 1.

My invention embodies a buffing attachment adapted to be quickly and conveniently mounted on and employed with commercial roll buffing machines, particularly the "Armstrong" light or medium duty buffing machines, without disturbing the machine settings or headstock and tailstock centers. The invention especially contemplates the employment of a cylindrical driving roll supported in axially fixed and true running axial alignment by and between the centers of the buffing machine, together with means for supporting parallel with the driving roll a drawing roll to be buffed, and means for moving the drawing roll into and out of grinding position and peripheral driving engagement with the driving roll. The driving roll thereupon functions to support in true alignment and rotate the drawing roll which is buffed to close cylindrical tolerances by being moved axially relative to and in peripheral grinding contact with the grinding wheel. The attachment is adapted to buff all types of anti-friction rolls from the smallest

2

gauge of spinning rolls to the largest roving and draw frame rolls, including rolls with or without end gudgeons.

In the drawings I have illustrated my attachment as applied to an "Armstrong" buffing machine in which 5 10 indicates a grinding wheel mounted to rotate on a fixed axis on the machine frame 12. A table 14 is mounted to slide on ways 15 (one shown in Fig. 4) parallel with the grinding wheel axis, a hand wheel 16 with pinion 17 and rack 18 being provided for thus moving the table. A rock shaft 20 is mounted in bearings 22 on the table 14. A headstock 24, including a motor 26, and a tailstock 28 are mounted on the shaft for rocking movement therewith. In the normal operation of the machine, the work is carried by and between the headstock and tailstock centers, and means including an adjusting knob 30 cooperating with a stop on the table are provided for limiting pivotal movement of the shaft in a direction bringing the work into contact with the grinding wheel.

20 The attachment comprising my invention includes a fluted driving roll 32 supported by and between the headstock and tailstock centers 33 and 34, and cooperating means mounted on the shaft 20 for supporting a drawing roll 36 to be buffed and including means for bringing the drawing roll into and out of grinding position and driving engagement with the driving roll.

25 The shaft 20 is of hexagonal contour (Fig. 4) and includes oppositely disposed V-flats 38 disposed horizontally as illustrated in Fig. 4. A frame 40 includes two forwardly facing V-elements 42 for engaging the shaft and two U-shaped clamping straps 43 having V-closed ends cooperating with the V-flats to secure the frame to the shaft. A saddle 44 extends through the legs of each strap and carries a clamping screw 46 for engaging the frame, tightening of the screws being adapted to draw the V-surfaces into tight engagement and secure the frame rigidly to the shaft.

30 Two spaced work supporting members 48 are mounted on the frame in alignment parallel with the driving roll 32 by mechanism hereinafter described. Each such member includes a forwardly facing horizontal guide-way 50 receiving therein the head 52 of a bolt for clamping thereto a roll supporting bracket 54. Each bracket carries a forwardly extending bar 56 V-notched at 58 35 at its front end to receive and support the drawing roll to be buffed. Outside plates 60 are secured to the bars by screws 62 for confining the drawing roll at its ends in the manner illustrated in Fig. 2.

35 A pair of forwardly extending bars 64 are rigidly fixed to each work supporting member 48 by screws 65 and the two members 48 are mounted on the frame 40 for independent pivotal movement about a common axis 66. Each such mounting comprises a bolt 68 pivoted at its bottom end to the frame at said axis and carrying a block 70 at its top end disposed between the pair of bars 64 and pivoted thereto on a bolt 72, the block 70 abutting against a nut 73 on the bolt 68. A compression spring 74 on each bolt engages at its top end against the block and at its bottom end against a nut 76 threaded to the bolt 68. Adjusting of the nut 76 is adapted to vary the compressive thrust of the spring against the block.

40 A T-shaped member 78 is pivoted at 79 at its bottom end to and between two rearwardly extending lugs 80 carried by the frame. An operating handle 82 is carried by and extends rearwardly from the member 78 and the top end of the member 78 carries a rod 84 loosely engaging the two work supporting members 48 thereon at its ends. Pivotal movement of the member about the axis 79 is adapted to move the drawing roll into and out of grinding position and engagement with the driving roll. A stop screw 86 carried by each bolt

68 is positioned to engage the shaft 20 and limit forward movement of the brackets.

The attachment is adapted for use in buffing anti-friction rolls having end gudgeons as illustrated in Fig. 2 or without end gudgeons as illustrated in Fig. 3. When the former are buffed, the brackets 54 will be adjusted to receive the end gudgeons of the drawing rolls and support them between the plates 60 as illustrated in Fig. 2. When the latter are buffed, the plates 60 will be removed and the brackets adjusted to support the axle 88 inwardly of the rolls 90 as illustrated in Fig. 3.

The buffing machine illustrated embodies mechanism including the knob 30 for pivotally adjusting the shaft 20, thereby properly positioning the driving roll 32 and the drawing roll 36 relative to the grinding wheel (Fig. 4). The parts are shown in the roll buffing position in full lines in Fig. 4 and by pushing of the handle 82 downwardly the parts are moved to the inoperative position wherein the drawing roll is illustrated in broken lines. A bar 92 carried by the member 78 is adapted to engage the lugs 80 to provide a stop limiting rearward movement of these parts.

A drawing roll 36 to be buffed is dropped into the V-shaped notches 58 while the parts are in retracted position. The handle 82 is then raised to pivot the parts forwardly to the position of Fig. 4. The rolls 90 or 94 thereupon pass into peripheral contact with and beneath the driving roll 32 and are stopped at a point wherein the axis of the drawing roll is beyond a center line connecting the driving roll axis with the axis 66. The compression springs 74 permit this movement and serve to maintain the drawing rolls in driving contact with the driving roll beyond the line of dead center described and in position to contact the grinding wheel. Thus the bolts 68 together with the springs 74 and co-operating parts comprise spring loaded toggle mechanism for resiliently maintaining the drawing roll in grinding and driving position when the work supporting members 48 are moved to their foremost position. The buffing operation is then effected by rotation of the hand wheel 16 to move the table 14 along the ways 15 whereupon the rolls 90 or 94 are buffed by contact with the grinding wheel.

It is particularly pointed out that the brackets 54 are independently mounted on the frame 40 by connecting mechanism including the bolts 68 and are loosely connected to the rod 84 whereby each bracket is free to move forwardly to the position permitted by its stop screw 86. These screws are also independently adjustable to positions permitting simultaneous contact of the two drawing rolls with the grinding wheel, it being understood that the limit buffing movement of the rolls into contact with the grinding wheel is determined and controlled by the knob 30 through its control of the shaft.

Having thus disclosed my invention what I claim as new and desire to secure by Letters Patent is:

1. In a drawing roll buffing machine embodying a grinding wheel, two rotatably mounted and axially aligned centers laterally of and axially parallel with the grinding wheel, means providing for relative axial movement of the grinding wheel and centers and power means for rotating one of the centers, an attachment comprising a cylindrical driving roll supported in axially fixed and true running axial alignment by and between the centers, work supporting means including two spaced members for rotatably supporting parallel with the driving roll a drawing roll to be buffed, means for mounting the work supporting means in operative position on the machine for simultaneous movement of said members toward and from the driving roll, and means for moving the work supporting means forwardly and rearwardly respectively to bring the drawing roll into and out of peripheral driving engagement with the driving roll and into and out of position to be engaged by the grinding wheel.

2. The attachment defined in claim 1 plus independent resilient means respectively operative on two said members for pressing and holding the drawing roll resiliently in driving engagement with the driving roll.

3. The attachment defined in claim 1 plus means including an operating handle pivotally supported on the machine and having a cross bar connected to said two spaced members for simultaneously moving them forwardly and rearwardly to bring said drawing roll into and out of driving engagement with the driving roll.

4. In a drawing roll buffing machine embodying a grinding wheel, two rotatably mounted and axially aligned centers laterally of and axially parallel with the grinding wheel, means providing for relative axial movement of the grinding wheel and centers, power means for rotating one of the centers and a shaft laterally of and parallel with the centers, an attachment comprising a cylindrical driving roll supported in axially fixed and true running axial alignment by and between the centers, work supporting means including two spaced members for rotatably supporting parallel with the driving roll a drawing roll to be buffed, means mounting the work supporting means on said shaft for pivotal movement toward and from the driving roll about an axis parallel with the shaft and driving roll, and means for moving the work supporting means about said axis forwardly and rearwardly respectively to bring the drawing roll into and out of peripheral driving engagement with the driving roll, and into and out of position to be engaged by the grinding wheel.

5. The attachment defined in claim 4 in which the work supporting means includes a frame having said two spaced members independently pivoted thereto on a common axis parallel with the shaft and driving roll and in which the means for moving the work supporting means is connected to and moves both said members simultaneously to bring said drawing roll into and out of engagement with the driving roll, and means for clamping the frame to the shaft.

6. The attachment defined in claim 5 plus two compression springs respectively associated with the two spaced members for pressing and holding the drawing roll resiliently in driving engagement with the driving roll.

7. The attachment defined in claim 6 in which the means for moving the work supporting means about said axis forwardly and rearwardly comprises a T-shaped member connected to the two spaced members and pivoted to the frame, and an operating handle carried by the T-shaped member.

8. The attachment defined in claim 4 plus stop means for limiting said forward movement of the work supporting means to a position wherein the axis of the drawing roll is beyond a center line connecting the driving roll axis with the first-named axis, and resilient means for holding the work supporting means in such forward position.

9. In a drawing roll buffing machine embodying a grinding wheel, two rotatably mounted and axially aligned centers laterally of and axially parallel with the grinding wheel, means providing for relative axial movement of the grinding wheel and centers and power means for rotating one of the centers, an attachment comprising a cylindrical driving roll supported in axial fixed and true running axial alignment by and between the centers, two spaced members for rotatably supporting parallel with the driving roll a drawing roll to be buffed, means independently mounting said members on the machine for pivotal movement about a common axis toward and from the driving roll, means connected to both members and adapted simultaneously to move them forwardly and rearwardly respectively to bring the drawing roll into and out of peripheral driving engagement with the driving roll and into and out of position to be engaged by the grinding wheel.

gaged by the grinding wheel, and adjustable stop means carried by each member for limiting its forward movement.

10. The attachment defined in claim 1 plus spring loaded toggle mechanism for resiliently maintaining the drawing roll in said driving engagement with the driving roll and in position to be engaged by the grinding wheel.
